METHOD OF PICKLING METAL

Nathan H. Schermer, Detroit, Mich.

Application October 19, 1936, Serial No. 106,365

1 Claim. (Cl. 148—8)

This invention relates to the pickling of metals, but has reference more particularly to a novel method of pickling metals in the form of sheets and strip.

5 A primary object of the invention is to provide a method of pickling metals wherein a more thorough pickling or cleaning is effected than is possible in the usual methods of pickling, and in a fraction of the time and with much less material and equipment than is required in pickling by such usual methods.

10 A further object of the invention is to provide a method of the character described which is preferably continuous in character.

15 To the accomplishment of the foregoing and related ends, said invention, then, consists of the steps hereinafter described and particularly pointed out in the claim, the following description setting forth in detail one approved method 20 of carrying out the invention, such disclosed method, however, constituting but one of the various ways in which the principle of the invention may be used.

The figure is a diagrammatic central vertical section.

25 The method, broadly stated, consists in flexing or stretching the metal while exposed to the action of the pickling solution. This flexing or stretching can be accomplished by the use of a scale breaker or roller leveler immersed in the 30 pickling bath, or by means of an electromagnetic vibrator which acts on the metal while it is so immersed.

The metal is preferably drawn or pulled 35 through the pickling bath by the flexing means or auxiliary devices, such as pinch rolls, and is flexed first in one direction and then in the other direction so that both surfaces of the metal are bent or flexed. Since the scale or oxide adhering 40 to the metal has considerably less ductility than the metal itself, the flexing causes the scale to crack and break off, at least the flexing is so performed as to accomplish this result. In some cases, the flexing is carried to a point which results in slightly stretching the metal.

45 As the scale cracks, the pickling solution immediately wets the bared metal and pickling takes place much more rapidly than in the case where the metal is first flexed outside the pickling bath and then passed through such bath. In the former case, the heat generated by the flexing seems to energize the pickling solution and causes the scale to readily break off, while in the latter case, the scale rarely breaks off and the base 50 metal is therefore not readily wetted. In most hot rolled metals, the scale, owing to the presence of pits and other surface defects, is tightly anchored to the metal, and is extremely difficult to remove by the usual pickling methods, such re-

moval usually requiring prolonged pickling resulting in considerable loss of metal and over-pickling. In demonstrating my method in a simple beaker, two pieces of scaled metal are immersed in the pickling solution, one being 5 flexed while so immersed and the other left intact. The piece which is flexed becomes pickled almost instantaneously where the scale is broken, but several minutes are required before pickling 10 of the other piece begins.

The flexing or stretching apparatus is preferably made of an acid-resisting metal, which will operate in a sulphuric acid bath for long periods with very little loss in weight. Such apparatus can be installed in existing pickling tanks, and 15 can be so arranged as to be readily removable from the tank, and in a manner similar to that in which tinning equipment is removed from a tin plating apparatus.

By way of example, there is shown in the 20 accompanying drawing apparatus which may be utilized in carrying out the method. Such apparatus, as shown, comprises a pickling tank 1 containing a pickling solution 2. The tank contains a multiplicity of rollers 3 extending transversely 25 of the tank and in staggered arrangement longitudinally of the tank. The rollers 3 are, as shown, immersed in the pickling solution, that is to say, the rollers are disposed below the level of the solution in the tank. The strip S, which is to be pickled, is caused to pass over some of the rollers and under the upper set of rollers through the solution in the manner shown, being drawn through the tank by suitable pinch rollers, not shown. This passage of the strip S between 30 the upper and lower set of rollers 3, flexes the strip alternately in opposite directions. All of the flexing, it may be noted, is performed while the strip is immersed in the pickling solution.

35 Other modes of applying the principle of my invention may be employed, instead of the one explained, change being made as regards the method herein disclosed, provided the step or steps stated by the following claim or the equivalent of such stated step or steps be employed.

40 I therefore particularly point out and distinctly claim as my invention:

The method of pickling metal in strip form 45 which comprises drawing said strip through a pickling solution, flexing it in one direction, then flexing it in a reverse direction from the first direction and then flexing it in the first direction and repeatedly flexing portions of said strip in such manner while it is immersed, said flexing being sufficient in extent to break the scale on 50 said strip and permit wetting of the bared base metal by the solution.

NATHAN H. SCHERMER.
